ABSTRACT

The invention relates to a flexible fan comprising, a boss portion and a plurality of fan blades radially extended from the boss portion and integrally formed therewith, the boss portion and the fan blades being of one piece construction and made of synthetic resin material, the flexible fan being characterized in that, α shows an angle of inclination of a wing chord against the rotational direction of the blade and β shows an angle against the wing chord of a leading edge portion of the fan blades, and $\alpha \leq \beta$ is represented.

FIG. 6

1
FLEXIBLE FAN

BACKGROUND OF THE INVENTION

This invention relates to improvements in and relating to a leading edge portion of a fan assembly for cooling automotive engine, especially adapted for use on automotive vehicle.

With the sudden development of the motorization, for example, as to the material of a fan for cooling automotive engine the fan integrally formed with the synthetic resins, such as polypropylene, nylon and so on, is adapted.

However, on the other hand it doesn't always follow that the road conditions are satisfactory for running of the vehicle, if circumstances require the vehicle to run on a flooded road not only in the rainy season, but also in the normal state. In that case the water is driven up by the front portion of the tire that is, the lowest portion of the fan is deformed and a lower part of the fan blade is flooded, so that the blade is unusually deformed by the impact force of the water. The fan is susceptible to damage by contacting the radiator.

Therefore, in the conventional fan a large gap between the blade and the radiator is necessary in order to prevent the fan from contacting with the radiator, or the thickness of the leading edge portion is reduced or a reinforced material is supplied. However, the cooling efficiency of the vehicle engine is reduced and an unreasonable arrangement in the engine compartment is necessary. The abovementioned drawbacks of the former is not fully overcome by the latter and further the weight of the fan blade is increased and the cooling efficiency of the vehicle engine is reduced in the latter.

SUMMARY OF THE INVENTION

It is, therefore, an object of the present invention to provide an improved fan assembly adapted for obviating the aforementioned drawbacks of the conventional fan assembly.

It is another object of the present invention to provide an improved fan assembly for eliminating the displacement of the leading edge portion of the blade toward the radiator when the blade encounters a flooded area.

It is still another object of the present invention to provide an improved fan assembly for raising the cooling efficiency of an engine by minimizing the gap between the radiator and the fan.

BRIEF DESCRIPTION OF THE DRAWINGS

Various other objects, features and attendant advantages of this invention will be more fully appreciated as the same becomes better understood from the following detailed description when considered in connection with the accompanying drawings, wherein like reference characters designate like or corresponding parts throughout the several views and wherein:

FIG. 1 is a front view of the fan assembly of this invention, but partially illustrated;

FIG. 2 is a sectional view taken along the line II-II of FIG. 1;

FIG. 3 is a view similar to that of FIG. 2, illustrating, however, a second embodiment of this invention;

FIG. 4 is a view similar to that of FIG. 2, illustrating, however, a third embodiment of this invention;

2

FIG. 5 is a distributive view of pressure operating the blades, when blades are flooded;

FIG. 6 is a view showing the deformed condition of blades when the blades are flooded; and

FIG. 7 is a view similar to that of FIG. 2, illustrating, however, a fourth embodiment of this invention:

DESCRIPTION OF THE ILLUSTRATED EMBODIMENTS

10 Referring now to the drawings, and more particularly to FIG. 1 thereof, the fan assembly of this invention will be described hereinbelow in detail.

In this Figure, the reference numeral 10 designates a fan boss and a plurality of blades 11 are radially extended from an outer peripheral portion 12 of the fan boss 10. The fan boss 10 and the blades 11 are integrally formed and made of such as synthetic resin. The reference numeral 13 is a pilot hole for connecting with a pulley seat, not shown, and a plurality of bolt holes 14 is provided on the fan boss 10. The ventilation is generally ventilated almost parallel to a rotational axle, not shown. According to FIG. 2, the incidence angle against a rotational direction 15 of a warped line 16 of the blades 11 in a leading edge portion 18 is zero or a little negative angle is applied to the leading edge portion 18. That is to say, supposing that an angle of inclination of a wing chord 17 against the rotational direction 15 of the warped line 16 is α_1 , and angle β_1 , against the wing chord 17 of the leading edge portion 18 is nearly equal to the angle α_1 or the angle β_1 is only larger than the angle α_2 .

Next referring to FIG. 2, the reference numeral 18a shows a leading edge portion of a conventional blade, and assuming that an angle against a wing chord 17a of the leading edge portion 18a against the extension of the warped line 16 is β_2 , an angle α_2 of inclination of the wing chord 17a against the rotational direction 15, is larger than the angle β_2 of the leading edge portion 18a and the leading edge portion 18a is spread from the rotational direction 15 in the upper direction (toward the radiator, not shown). A groove 20 is provided on the middle portion of the blade 11 so as to easily bend a trailing edge portion 19 of the blade 11 when the hydraulic pressure or wind pressure is operated to the blade 11 as shown in FIGS. 1 and 2. An arc-shaped groove or a thin face 21 may be formed on the trailing edge portion 19 of the blade in order to specially bend the trailing edge portion 19 thereof as viewed in FIG. 7.

As to the arrangement of the groove 20, it can be on a surface 22 or the inside surface 23, or on both the surface 22 and the surface 23 as shown in FIG. 3. When the groove 20 is, however, provided on the surface 22 the ventilation speed of the surface 22 is swifter than when on the inside 23 in the operating state, namely, Reynolds number is high and the fan efficiency is reduced, therefore it is desirable to provide the groove 20 on the inside 23. It is not necessary to provide the groove 20, the arc-shaped groove, or the thin face 21 in this invention as viewed in FIG. 7.

When the blade 11 reaches a flooded area 24 in the increasing state of the number of fan rotation as seen in FIG. 6, the impact force at this moment and the increasing pressure force on the inside 23 of the blade 11 are very large and the positive pressure is normally applied to the inside 23 of the leading edge portion 18 as shown in FIG. 5, but the negative pressure is supplied

thereto in this invention. The positive pressure is provided on the inside 23 of the trailing edge portion 19 also in the normal blade or in the blade 11 according to this invention.

However, when the blade 11 reaches the flooded area 24 the blade 11 is bent almost parallel to the warped line 16a of the blade 11 in the normal fan and passes the flooded area 24, and then the blade 11 is restored to the original state.

The warped line 16 of the leading edge portion 18 of the blade 11 is almost parallel to or at a slight negative angle to the rotational direction 15 so that only the impact force is applied to the leading edge portion 18 also at the moment of arrival at the flooded area 24 or thereafter, and the water pressure is supplied to the inside 23 of the blade 11 at the trailing edge portion 19 as viewed in FIG. 5 so that only the trailing edge portion 19 tends to bend upwards in FIG. 6. The bending force is, however, absorbed by the groove 20 provided on the inside 23 of the blade 11. Therefore, the bending force does not influence the leading edge portion 18 and so the leading edge portion 18 of the blade 11 is not displaced with respect to face of the fan.

The result of the experiment between the fan according to this invention and the fan according to conventional type is showed as follows;

Experimental condition	Conventional fan	Fan of this invention
The depth of water of road surface	200 mm	—
Vehicle speed	20~25km/h	—
Thickness of blade	2.1 mm	3.8 mm
leading edge portion	2.1 mm	2.1 mm
centering portion	1.4 mm	1.4 mm
trailing edge portion	2.1 mm	2.1 mm
Angle of inclination	$\alpha_2=26^\circ 42'$	$\alpha_1=26^\circ 42'$
Angle of inclination	$\beta_2=20^\circ$	$\beta_1=34^\circ$
Blade span	115 mm	115 mm
Effective width of blade	77.1 mm	82.4 mm
Rate to the chord length of the bent portion of the leading edge	0	8~30%
Result	deflection of the leading edge of fan (number of fan rotations 3000~3500 r.p.m.)	21~22 mm
		7~8 mm

The abovementioned rate to the chord length of the bent portion of the leading edge shows the rate against the chord length of the length projected to the bent portion of the leading edge on the chord length.

It is desirable, that the rate to the chord length of bent portion is 8~30 percent. But when the rate reaches over 8~30 percent the cooling efficiency becomes bad, and when the rate is under 20~24 percent the effect for preventing the bending becomes little.

Obviously many changes and modifications of the

present invention are possible in light of the foregoing teachings. It is to be understood, therefore, that within the scope of the appended claims, the invention may be practiced otherwise than as specifically described herein.

Accordingly,

What is claimed is:

1. A flexible fan comprising:

a boss portion; and

a plurality of fan blades radially extended from said boss portion and integrally formed therewith; said boss portion and plurality of fan blades being of one piece construction and made of synthetic resinous material;

said flexible fan having an angle α between a wing chord and the rotational direction of said fan blades and an angle β between said wing chord and a tangent line of a warped line in the leading edge of a leading edge portion in which α is not greater than β , said warped line having a bent portion at said leading edge portion, and the bending rate of said bent portion in said leading edge portion against a chord length of said fan blade is between 8 and 30 percent.

2. The flexible fan as set forth in claim 1, wherein a groove is provided on said fan blade so that the trailing edge portion of said fan blade is easily bent.

3. The flexible fan as set forth in claim 2, wherein said groove is formed on said trailing edge portion.

4. The flexible fan as set forth in claim 2, wherein a thin face is formed on said trailing edge portion.

5. A flexible fan comprising:

a boss portion; and

a plurality of fan blades radially extended from said boss portion and integrally formed therewith; said boss portion and plurality of fan blades being of one piece construction and made of synthetic resinous material;

said flexible fan having an angle α between a wing chord and the rotational direction of said fan blades and an angle β between said wing chord and a tangent line of a warped line in the leading edge of a leading edge portion in which α is not greater than β , said warped line having a bent portion at said leading edge portion, and the bending rate of said bent portion in said leading edge portion against a chord length of said fan blade is between 20 and 24 percent.

6. The flexible fan as set forth in claim 5, wherein a groove is provided on said fan blade so that the trailing edge portion of said fan blade is easily bent.

7. The flexible fan as set forth in claim 6, wherein said groove is formed on said trailing edge portion.

8. The flexible fan as set forth in claim 6, wherein a thin face is formed on said trailing edge portion.
